FRANK T. COPE, OF SALEM, OHIO, ASSIGNOR TO THE ELECTRIC FURNACE COMPANY,
OF SALEM, OHIO, A CORPORATION OF OHIO

RESISTOR GRID AND METHOD OF SUPPORTING SAME

Application filed September 17, 1923. Serial No. 663,275.

This invention relates to electric furnaces and more particularly to the resistance elements for producing the heat in the furnace and has for its objects to provide a resistor 5 grid formed of solid metal of a cross sectional shape to radiate the heat rays into the interior of the furnace at an angle to the furnace wall, and comprising a single bar bent into a plurality of parallel sections 10 so proportioned as to produce a radiating surface considerably greater than the wall surface covered by the grid, means being provided for supporting the grid spaced from the furnace wall and in a manner 15 to permit expansion and contraction of the grid without allowing the sections thereof to move out of their parallel relation to each other.

The above and other objects may be attained by constructing the resistor grid and supporting means in the manner illustrated in the accompanying drawings, in which—

Figure 1 is a front elevation of a resistor grid embodying the invention, showing the 25 same mounted upon a fragment of furnace wall;

Fig. 2, a section of the grid on the line 2—2, Fig. 1;

Fig. 3, a section of the grid on the line 30 3—3, Fig. 1;

Fig. 4, a section of the grid on the line 4—4, Fig. 1;

Fig. 5, a transverse sectional view through the wall showing an end elevation of the 35 grid and the terminal thereof;

Fig. 6, a perspective view of the terminal stud;

Fig. 7, a front elevation of the terminal;

Fig. 8, a perspective view of one of the 40 supporting hooks;

Fig. 9, a similar view of one of the lower spacing hangers; and

Fig. 10, a modified cross section of the grid.

Similar numerals refer to similar parts throughout the drawings.

A portion of a furnace wall built of refractory brick or the like, is indicated at 1 and the resistor grid is formed of a continuous bar of metal bent at intervals to produce

a plurality of vertical parallel portions 2 of the general cross sectional shape shown in Fig. 3, the curved upper ends thereof being preferably flattened as shown at 4, giving the cross sectional shape shown in Fig. 2, 55 while the lower curved ends are provided with the depending studs 5.

A recommended general cross sectional shape of the grid is T-shaped, as shown in Fig. 3, the base 6 having the inclined side edges 7, while the flange or rib 8 is tapered toward its point which is rounded as at 9.

Or the general cross sectional shape of the grid may be substantially channel shape, as shown in Fig. 10, the base 6^a and the flanges 60 or ribs 8^a having inclined sides; in either case the grid bar being flanged or ribbed to give it strength and rigidity.

With this cross sectional shape, the greater portion of the surface of the grid is located at an angle to the normal plane of the grid, thus radiating the majority of the heat rays into the heating chamber of the furnace at an angle to the furnace wall.

The grid is supported at its upper edge portion by the hooks 10 which engage the flattened portions 4 of the grid. Each hook is provided with the flattened shank 11 received in the flat socket 12 formed in the upper edge of the adjacent brick in the refractory wall 1, and depending lugs 13 and 14 are provided at the forward and rear ends of the shank to prevent longitudinal movement of the shank within the wall.

The depending studs 5 upon the lower ends of the grid bars are extended through the squared apertures 15 formed in the lower supports 16, which are also provided with the flat shanks 17 received in the notches 18 in the upper faces of the adjacent bricks. A shoulder 19 is formed at the inner end of the shank and a depending lug 20 at the outer end thereof to prevent longitudinal movement of the support in the wall.

Each extremity of the grid is connected to a terminal stud 21 which is extended through a suitable opening 22 in the brick wall of the furnace, the inner end thereof being provided with the flat head 23 which

is welded to the adjacent extremity of the grid.

A terminal 24 is connected to the outer end of each of the terminal studs 21, having the split socket 25 which receives the end of the stud, clamping bolts 26 clamping the same tightly upon the stud. Sockets 27 are formed in the terminal into which the ends of the cables 28 are soldered or 10 otherwise connected.

Owing to the cross sectional shape of the grid and the conformation of the same, the radiating surface of the grid is equal to about twice the area of wall surface upon 15 which the grid is mounted, thus producing a maximum of heat from a given area.

By referring to Figs. 3 and 10, it will be seen that the cross sectional shape of the grid is such that the greater portion of the 20 radiating surface is arranged to radiate the heat rays inward toward the interior of the heating chamber of the furnace, and away from the furnace wall at an angle thereto, thus radiating considerably more heat into 25 the interior of the heating chamber than is possible with the usual constructions now in use.

As the studs 5 upon the lower ends of the grid bars are extended loosely through the 30 openings 15 in the lower supports, the grid may expand as the temperature of the same is increased, without causing any buckling or warping, since the entire weight of the grid is supported from the upper hooks.

35 The upper hooks engaging the loops at the upper end of the grid and the lower supports engaging the studs upon the lower ends of the grid bars, prevent lateral distortion of the grid under high temperature, thus 40 preventing adjacent portions of the grid from coming into contact with each other when they are expanded by the heat.

Generic claims for the broad inventions and specific claims for the channel shaped 45 grid bar, which are illustrated and described but not claimed here, are made in application Serial No. 451,976, filed May 13, 1930, as a division of this application.

I claim:—

50 1. A grid formed of a bar of substantially T-shaped, cross sectional shape, bent upon itself to provide a plurality of vertical parallel portions connected at alternate ends by curved portions, the curved portions at 55 the upper end of the grid being of substantially flat cross sectional shape and supporting hooks engaging said upper curved portions.

60 2. A grid of the character described formed of a bar of substantially T-shape cross section, the side faces thereof being inclined to radiate the major portion of the heat rays away from the base in the direction of the flange side of the bar.

65 3. In combination with a wall, a resistor

grid formed of a bar bent upon itself at intervals and supports extended entirely through the wall and supporting the grid spaced from the wall and provided with means for preventing longitudinal movement of the supports in the wall, said means including shoulders at each end of the supports for engagement with the surfaces of the wall.

In testimony that I claim the above, I 75 have hereunto subscribed my name.
